UNITED STATES PATENT OFFICE.

ALFRED H. SMITH, OF CHAPPAQUA, NEW YORK.

METHOD OF HANDLING FREIGHT, EXPRESS, AND THE LIKE.

1,407,596.

Specification of Letters Patent. Patented Feb. 21, 1922.

Original application filed June 9, 1920, Serial No. 387,517. Divided and this application filed April 26, 1921. Serial No. 465,348.

To all whom it may concern:

Be it known that I, ALFRED H. SMITH, a citizen of the United States, residing at Chappaqua, Westchester County, in the 5 State of New York, have invented certain new and useful Improvements in Method of Handling Freight, Express, and the like, of which the following is a specification.

In the system now in vogue in handling 10 freight and express matter it is necessary for the shipper, in many instances, to crate his goods then haul them to the station to a receiving platform from whence it is loaded onto the car and this series of operations is 15 repeated after the goods reach the destination city. In the case of a shipment of merchandise, etc., the manufacturer must construct packing cases which involves a material expense.

20 In the billing of less than carload lots of merchandise for shipment, each box and package must be itemized and counted. By this invention, the lading would be placed in the compartment at shipper's load and 25 count, would be sealed and locked and the compartment would be handled intact; the "way billing" will be reduced to a minimum; the reciting in detail of what the compartment contains will be eliminated. On 30 some railroads, 80% of the billing is composed of these small items, and the checking of such takes time, involves expense and involves a great amount of labor.

As regards the burglary of cars and the 35 loss and damage of freight; this mostly occurs between the time when the shipment is delivered to the freight house at the point of origin and the time it is delivered to the freight house at destination, for the reason 40 that the average shipment passes through a large number of hands, is liable to breakage and gives opportunity for removing a portion of the merchandise.

In many instances cars are broken into 45 while standing in yards and also while the trains are in motion, the packages being thrown out along the road and removed by confederates.

A great deal of damage also occurs by reason of rough handling in freight houses by 50 careless employees or because the container is of insufficient strength. Also the constant re-handling of packages is responsible for breakage or partly destroyed goods.

It should also be taken into account that in 55 addition to the actual loss and damage, there is a considerable loss to the public by reason of the fact that what they have purchased and shipped fails to arrive, or upon arrival, is in a damaged condition. This delays 60 sales, and, in the case of castings and similar building material, delays construction, results in great inconvenience and loss of money so that the actual loss and damage, 65 while it can be measured in terms of money, cannot be measured as to actual loss because of its importance at a given time. Furthermore, with this invention, shipments will not be so much exposed to the elements.

Reports show that loss and damage on L. 70 C. L. (less than car lots) on one railroad for six months ended February 29th, 1920 was \$2,161,680. A study shows that 11% of freight revenue is derived from L. C. L freight. On this basis during the six 75 months this traffic produced \$10,239,682 revenues on said railroad. The losses shown; therefore, bear a ratio of 21 per cent to the amount received for carrying the freight. Practically 80% of the "billing" is due to 80 L. C. L. freight. The elimination of this alone is a very material item.

Under the present rate of wage scale the handlings of the individual packing cases from dray to platform and from platform to 85 car, from car to platform and from platform to dray is a very large item of expense in the handling of express and freight matter.

One of the objects of my invention is to provide individual freight or merchandise 90 compartments to shippers at the factory or stores into which their goods may be placed without being previously crated and the compartments loaded and placed upon a dray from which it is lifted onto a car or 95 platform at the railroad station there being a plurality of these compartments for each car so that the individual compartment may be lifted bodily with its contents from the car at the point of its destination and placed 100 upon a truck to be delivered to the consignee at the store or factory who will unpack the compartment and have it returned to the railroad. By this system it will be seen that a number of handlings of freight merchandise, parcel post and express matter is eliminated thereby cutting down the cost besides 105 which the lading is thoroughly protected

from the inclemencies of the weather while in transit and thoroughly protected against theft.

Another object of this invention is to place a plurality of these compartments on a single car, in juxtaposition, with the door of one compartment facing a wall of the next adjacent compartment or an abutment whereby the doors are held in closed position while enroute. The doors being adjacent the walls of the next compartment or an abutment cannot be opened while the compartments are in transit on the railroad.

Another object of my invention is to provide means whereby these compartments may be anchored and stabilized on the car against accidental displacement and to provide the compartments with suitable devices to which the chain of a crane may be attached whereby the compartments may be promptly lifted from the car by a crane and deposited on a delivery truck or platform.

Another object of my invention is to provide each compartment with compression members to prevent the buckling, twisting or distorting under the strain of the load in the act of lifting them by a crane from the car to the truck or platform.

Another object of my invention is to so construct each compartment that it will be braced to withstand the weaving of the car under service conditions.

With these and other objects in view my invention consists of the parts, and combination of parts, as will be hereinafter more fully set forth.

In the drawings:

Figure 1 is a detailed side elevation and vertical longitudinal section of a car and compartment embodying my invention.

Figure 2 is a top plan view of Figure 1, the compartment being partly in section.

Figure 3 is a transverse section of a car showing a compartment in position on it, the compartment being partially broken away to show the friction wedge lock between the car and compartment.

The reference numeral 1 designates a gondola car which may be of any desired or standard construction. In the present instance I have shown the end, 3, and side walls 4 of the car constructed of sheet metal, the end walls being provided with longitudinally extending corrugations, 5, which corrugations function as beams thereby materially strengthening the end walls against thrust. The upper edge of the end and side walls is reinforced by the angle iron 6.

60 In the present instance the interior of the body of the car is divided into a series of spaces by means of transverse members, 7, each end of which is connected to the angle iron 6, by the means of the gusset 8, as clearly shown in the drawings.

63 2 is a wedge element riveted to the inner

face of the side walls of the car, the wedge face being inclined downwardly and inwardly from the inner face of the side wall of the car. These wedge elements are, preferably, located at a point in the car diamet- 70
rically opposite the outside car stake 9, whereby the stake reinforces and supports the wedge element and side wall of the car against bulging outwardly.

Similar wedge elements are secured to the 75 opposite side walls of the car.

Wedge elements, 10, are secured to the end walls of the car, as shown in the drawings, and these elements are of the same construction as the wedge element 2. Wedge 80 elements 11 are secured to the transverse member 7 and consist of a substantially U shaped member 12 with its arms converging toward each other at the top whereby inclined wedges are formed along the same 85 angle and pitch as the wedge elements 2. The arms of the wedge member 11 are secured to a channel iron compression member 14.

From this it will be seen that there are 90 shown in the present embodiment eight wedge members for each space on the car.

The stakes 9 are each provided with a longitudinally extending corrugation which functions as a beam to support the side walls 95 of the car against bulging outwardly.

As stated the car is divided into a plurality of spaces, the number being dependent upon the length of the car, said spaces being designed to receive and retain against accidental displacement, a plurality of individual freight, merchandise, or parcel post compartments. 100

Inasmuch as all of the compartments are of the same construction it will be necessary only to describe one of them. The compartments are preferably constructed of sheet metal, the walls of the compartments may be provided with corrugations extending vertically of the compartments, or the walls may be of flat sheet metal. 105 110

These corrugations function as beams for the side walls whereby said walls may be constructed of comparatively thin metal without impairing the strength of the wall and the ability of the walls to withstand the shocks, strains and stress incidental to service conditions while the compartment is in transit on a car. 115

The side walls of the compartment are secured at the corners to an angle bar 16, the extreme end portions of the side sheets being extended beyond the corner and deflected outward at 17 so as to lie parallel. A corner cap 18 substantially U shaped in cross section is fitted on the extended ends 17, of the side walls and secured by means of rivets to the side wall of the compartment and angle iron 16 so that the rivets are common to the side wall, angle iron 16, and U 130

shaped cap 18. This corner formation very materially strengthens the corner joints of the compartment against twisting and other strains so that the compartment will remain 5 "in square" under all service conditions. In addition to the function of strengthening the corners of the compartment the U shaped corner cap 18, also functions to make a weather and dust proof joint in the corner 10 of the compartment. This U shaped cap 18 and extended portions 17 of the side wall terminate at a point above the bottom of the compartment. At each corner of the compartment I secure a wedge element 20 which 15 extends from the termination of the lower end of the corner cap 18 to a point in the plane of the floor of the compartment which wedge elements engage and co-act with the wedge elements 10 and 11 when the compartment 20 is lowered into position on the car thereby centering and locking the compartment in its proper position on the car.

On each side and one end wall of the compartment I provide wedge members 21 which are the counterpart of wedge members 2 and 11 reversely positioned with respect to and which also function with the corner wedge members of the compartment to center and lock the compartment in its 30 position when placed upon the car.

As shown in the drawing the door of the compartment is preferably corrugated to strengthen it against distortion and the joint between the free end of the door and the 35 end wall of the compartment may be of varied form, but of course the joint must be weather and dust proof. The door, 22, is provided with any suitable lock 23 and hinges 24.

40 The floor, 25, of the compartment is positioned above the lower edges of the walls of the compartment and is secured to the walls of the compartment by means of the channels 26 which function as spacing members 45 and sustain that portion of the walls projecting below the floor level against bending and distortion. This projection of the lower ends of the walls below the floor of the compartment also functions to prevent the floor 50 of the compartment coming in contact with any water that may accumulate in the car or on the platform.

At the top of the compartment there are angle irons extending along each wall of the 55 compartment, one leg of which angle irons is suitably riveted to the walls of the compartment. The angle irons 27 at the top of the compartment are shaped to the pitch of the roof. The roof is preferably a solid steel 60 roof and is composed of the sheets 28 and 29. The sheets 28 and 29 have the side marginal edges turned upwardly to form upstanding flanges over which are fitted a combined car-line and roof seam cap 30 thereby making

the joint between the upstanding flanges of 65 adjacent sheets weather and dust proof. These combined carlines and seam caps are flared outwardly at the eaves end thereby providing an extended bearing on the roof at the eaves. The roof sheets and the ends 70 of the combined cap and carline at the eaves are riveted together and to an angle iron 27. It will be seen from the drawing that the eaves end of the combined cap and carline and roof sheets are bent downwardly to form 75 a drip. At the sides of the compartment the roof sheets extend beyond the side walls and are riveted to an angle iron 27 which in turn is riveted to the side walls of the compartment. 80

On diagonal corners of the compartment, or on all four corners of the compartment, as may be desired, I secure gusset plates 32 to which are pivotally secured lifting loops 33 with which the chain of the crane may be 85 attached for the purpose of lifting the compartment.

While I have, for the purpose of describing and illustrating my invention, shown a specific form of compartment and arrangement of car to receive the compartments it will be understood that my invention is not limited to such specific constructions but on the contrary is generic to the broad idea of providing a compartment which may be 95 loaded by the shipper, placed upon a car adapted to receive it and removed from said car and delivered to the consignee with the shipment intact, and the loading of a series of such compartments on a car with the door 100 of each compartment adjacent a wall of another compartment, or an abutment which prevents the opening of the door while the compartment is in position on the car. It is also obvious that the underframe of the 105 car may be of a skeleton form.

Of course it is obvious that I may place a running board on the top of the compartments or design the car to have a running board somewhat similar to those on tank 100 cars.

This application is a division of my co-pending case, Serial Number 387,517, filed June 9, 1920.

What I claim is:

1. The method of loading a plurality of independent freight compartments on a car, which consists in arranging said compartments adjacent each other with the doors of each compartment facing a wall of the next 120 adjacent compartment whereby only the imperforate walls of the compartments are exposed to view when mounted on the car.

2. The method of loading a plurality of independent freight compartments on a car, 125 which consists in arranging said compartments adjacent each other with the doors of each compartment adjacent a stop on the

car, whereby the doors cannot be opened while the compartments are on the car.

3. The method of handling freight, merchandise, parcel post, and the like in less than car load lots which consists in packing the lading at the point of origin in a compartment at shippers load and count, locking and sealing the compartment, handling and loading the compartment intact on a car and giving a single way bill for the intact compartment, transporting the compartment to city of destination then lifting the compartment intact from the car and moving it on a truck to place of business of consignee.

4. The method of handling freight, merchandise, parcel post, and the like in less than car load lots, which consists in packing the lading at the point of origin in a compartment at shippers load and count, locking and sealing the compartment, handling and loading the compartment intact on a car and giving a single way bill for the intact compartment, anchoring the compartment on the car, transporting the compartment to city of destination, when lifting the compartment intact from the car and moving it on a truck to place of business of consignee.

5. The method of handling a plurality of less than car load lots of lading for the same or different points of destination on a railroad which consists in loading each lot of lading in its particular compartment at shippers load and count, locking and sealing each compartment, handling and loading the plurality of compartments on a single car with the door of each compartment adjacent a stop to prevent the opening of the door of the compartments while on the car, anchoring each compartment on the car, giving a single way bill for each intact compartment, transporting the compartments to their respective destination point on the railroad, removing the respective compartments intact from the car at their said points of destination and placing them intact on a truck and moving the compartments on a truck to place of business of consignee, whereby each compartment may be removed from a car without impairing the security of the other compartments and of the car.

In testimony whereof, I affix my signature.

ALFRED H. SMITH.
